UNITED STATES PATENT OFFICE.

OLOF A. NORLAND, OF CEDAR RUN, PENNSYLVANIA, ASSIGNOR OF ONE-HALF TO GEORGE A. GAMBLE, OF SAME PLACE.

DESIGN FOR A CLASP.

SPECIFICATION forming part of Design No. 25,826, dated July 21, 1896.

Application filed February 29, 1896. Serial No. 581,406. Term of patent 14 years.

To all whom it may concern:

Be it known that I, OLOF A. NORLAND, a citizen of the United States, residing at Cedar Run, in the county of Lycoming and State of Pennsylvania, have invented a new and original Design for a Pin or Clasp, of which the following is a specification.

This invention relates to a new and original design for a pin or clasp, and it has for its object to provide a design of this character which shall be both useful and ornamental.

The leading feature of the design resides in an elongated ovoid-shaped wire body having at its narrowed end a right-angularly-disposed spiral-shaped portion, and a pair of different-sized approximately **U**-shaped figures projected from the side of said spiral-shaped portion opposite the ovoid-shaped wire body and lying one within the plane of the other, said different-sized **U**-shaped figures having truly parallel sigmoidal side portions, the adjacent sigmoidal side portions of said **U**-shaped figures intersecting with each other and forming between the points of intersection a pair of elliptically-shaped figures, and between the outer ends of said **U**-shaped figures a **V**-shaped figure, said pair of elliptically-shaped figures together forming substantially an **8**-shaped figure.

In the drawings, Figure 1 is a perspective view of a pin or clasp embodying the herein-described design. Fig. 2 is a front elevation thereof. Fig. 3 is a side elevation of the same.

Referring to the accompanying drawings, the numeral 1 designates an ovoid-shaped wire body having a narrowed twisted end portion 2, directly adjacent to which is formed a right-angularly-disposed spiral-shaped portion 3. From one side of the spiral-shaped portion 3 of the wire body is projected a pair of different-sized approximately **U**-shaped figures 4 and 5, respectively, the figure 4 being illustrated as the smaller of the two figures and lying within the plane of the **U**-shaped figure 5. The said **U**-shaped figures 4 and 5 are provided with truly parallel sigmoidal side portions 6, the adjacent of which sigmoidal side portions intersect with each other at the points 7, to form a pair of aligned elliptically-shaped figures 8, and a **V**-shaped figure 9, between the outer ends of said **U**-shaped figures 4 and 5. The pair of elliptically-shaped figures 8 combine to form an **8**-shaped figure.

What I claim is—

The design for a pin or clasp herein shown and described.

In testimony that I claim the foregoing as my own I have hereto affixed my signature in the presence of two witnesses.

OLOF A. NORLAND.

Witnesses:

JOHN HILBORN,
W. E. GAMBLE.
